ELECTRONIC TIME DIVISION CHANNEL
SCANNING SYSTEM

Henry J. Koch, Belleville, N. J., assignor to National Union Radio Corporation, Orange, N. J., a corporation of Delaware

Application June 8, 1949, Serial No. 97,792

9 Claims. (Cl. 179—15)

1

This invention relates to communication systems of the multiplex kind, and more especially to multiplex systems of the pulsed channel type.

A principal object of the invention is to provide a simplified and efficient channel scanning arrangement for timed division multiplex transmission.

Another object is to provide an improved pulsed multiplex transmitter employing as the pulsed channel source an electron tube of the focussed rotary beam type.

Another object relates to a novel combination of rotary beam tube and a signal-controlled multi-section output tube, which tubes are interconnected to provide timed division multiplex signals having a relatively low noise level.

A feature of the invention relates to the combination of a rotary beam tube which acts as a multiplex channel pulse generator, a plural-section inverter tube, and a plural-section signal-controlled tube, which tubes are interconnected to provide an improved timed division multiplexing transmitter having a relatively low noise level.

A further feature relates to the novel organization, arrangement and relative location of parts which cooperate to provide an improved and efficient timed division multiplex transmitter.

In the drawing, which shows, by way of example, one preferred embodiment:

Fig. 1 is a schematic structural and wiring diagram of a multiplex pulsed transmitter according to the invention.

Fig. 2 is a series of pulse graphs explanatory of the operation of Fig. 1.

Fig. 3 is a schematic structural and wiring diagram of a multiplex receiver according to the invention.

Fig. 4 is a modification of Fig. 1.

Referring to Fig. 1, the numeral 1 represents schematically a tube of the focussed rotary beam type. For a detailed description of such a tube, reference may be had to "Proceedings of the I. R. E.", vol. 36, No. 11, November 1948, pages 1354-1357. The tube comprises a suitable evacuated enclosing envelope 2 containing a central electron-emitting cathode 3, provided with the usual internal and electrically-insulated heater filament or element 4. The cathode 3 may be of the type well-known in so-called indirectly-heated cathode tubes, for example in the form

2

of a metal sleeve having its external surface coated with electron-emissive material. Concentrically surrounding the cathode 3, are six metallic screens 5-10 which are spaced apart to form respective windows 11-16, all the windows being of the same dimensions and being equally spaced around the cathode 3. Each of the screen plates 5-10 also has a central window 17-22 of substantially the same dimensions as the windows 11-16. There are thus provided twelve windows of the same size, equally spaced around the cathode 3. Surrounding the screen plates, and in radial alignment with each of the respective windows, is a corresponding anode 23-34. While the drawing shows twelve of these windows and anodes, it will be understood that a greater or less number may be employed, depending upon the number of multiplex channels to be desired. Each of the screen plates 5-10 is provided with a separate lead-in 35-40, which lead-ins are connected to any well-known six-phase source of potential. The cathode 3 is returned to ground through a suitable bias resistor 21. The anode plates are likewise connected through respective lead-ins 41, 42, 43, etc. and through respective load resistors 44, 45, 46, etc., and thence in parallel to the positive terminal 47 of a suitable source of plate potential represented schematically by the battery 48. As explained in said application, by choosing the proper bias for the cathode 3 and for the various plates, the electron beam from the cathode is focussed into a substantially planar beam 49 whose transverse width is equal to or less than the transverse distance between the centers of the windows 11-22. As explained in said publication, the beam 49 is rotated synchronously at a predetermined rate controlled by the six-phase potential source connected to the screen plates 5-10. Therefore this beam successively completes a circuit through each of the twelve respective resistors 44, 45, 46, etc. Consequently as the beam rotates, it develops across the respective resistors, negative pulses 50, 51, 52, etc. (Fig. 2). Thus the pulses are spaced apart in time by a regular interval "t," and the recurrence time "T" is equal to "Nt," where "N" is the total number of anodes.

The pulses developed across the resistors 44, 45, 46, etc., are applied through respective coupling condensers 53, 54, 55, etc., to the respec-

tive control grids 56, 57, 58, etc. of another tube 59. This tube can be structurally substantially the same as that of tube 1, except that all the screen plates are electrically connected together and to the same positive potential 60. In other words, the electrons from the cathode 61 are not focussed into a planar beam, so that they are emitted simultaneously in all radial directions through the respective twelve windows 62, 63, 64, etc. of the screen plates. The central cathode 61 can be connected directly to ground and is surrounded by a positively charged grid 65 which acts as a space charge grid for the tube by being connected to a suitable positive direct current biasing source 66. In alignment with each of the grids 56, 57, 58, etc., are the respective output anodes 67, 68, 69, etc., which are connected to the positive direct current supply terminal 47 through respective load resistors 70, 71, 72, etc. The potential of the negative pulses 50, 51, 52, etc. are such that when they are impressed upon the respective grids 56, 57, 58, etc., they cut off plate current flow from the cathode 61 to the respective anodes 67, 68, 69, etc. Thus the negative pulses are converted into positive pulses across the respective resistors 70, 71, 72, etc. These positive pulses are applied through respective coupling condensers 73, 74, 75, etc., to respective switching control grids 76, 77, 78, etc., to another tube 79. This tube may comprise an evacuated envelope 80 containing a central electron-emitting cathode 81 which is surrounded by a positively-charged space-charge grid 82 supplied by a suitable positive direct current biasing potential from the source 83. Concentrically surrounding the grid 82 are the screen plates similar to the plates 5-10 of tube 1, but with all the plates electrically connected together and to the same positive direct current potential 84. Thus there are twelve windows 85, 86, 87, etc., equally spaced around the cathode 81, the grids 76, 77, 78, etc., being in alignment respectively with each one of said windows. Also concentrically surrounding the cathode in alignment with the said windows and located between these windows and the switching grids, is a similar series of signal input control grids 88, 89, 90, etc., a single output anode 91 concentrically surrounds all the electrodes, and is connected to the positive terminal 47 of the direct current power supply through a single plate load resistor 92, and thence to a common output terminal 93 which may lead to a suitable transmission line or channel. All the switching grids 76, 77, 78, etc., are connected through respective grid-leak resistors 94, 95, 96, etc., to the negative terminal 97 of a suitable direct current biasing source 98, so as normally to bias the switching grids 76, 77, 78, etc., to plate current cutoff. Each of the signal input grids 88, 89, 90, etc., is connected through a suitable coupling condenser 99, 100, 101, etc., to respective signal input channels 103, 104, 105, etc. These signal input grids are biased through respective grid-leak resistors 106, 107, 108, etc., to a suitable negative potential 109 to maintain the various sections of the tube operating on the straight line portion of their control grid-plate current characteristic curve. From the foregoing description it will be seen that the tube 1 generates regularly recurrent and spaced negative pulses which when applied to the tube 59, produce at the grids 76, 77, 78, etc., corresponding positive pulses. However the amplitude of these positive pulses can be chosen with respect to the negative bias on the grids 88, 89, 90, etc.,

so that plate current does not flow from the cathode 81 to the anode 91 except upon the timed coincidence of a positive pulse applied to a switching grid, and a positive signal pulse applied to the corresponding signal input grid from the respective signalling channel. On the other hand, the magnitude of the positive pulses applied to the switching grids can be proportioned with respect to the negative bias on the signal grids, so that the signal potentials applied from the respective channels 103, 104, 105, etc., cause a modulation of the plate current flowing from the cathode 81 to the anode 91 respectively through the successively switched-in sections of the tube.

It has been found that by this particular combination of tubes, and the particular manner of generating the switching or timing pulses by means of a rotary beam tube which is separate from the channel output tube 79, a considerable reduction in signal-to-noise ratio is obtained in the output signals at terminal 93. It will be understood, of course, that at the receiver any well-known channel distributor can be provided for connecting the various receiving channels into circuit, with terminal 93 in timed coincidence with the impingement of the electron beam 49 on the successive anodes 23-34. Preferably this distributor may comprise a rotary beam tube 110 (see Fig. 3), similar to tube 1, having its focussed electron beam rotating in timed synchronism with the beam 49. Thus this tube may comprise a central electron-emitting cathode 111 which is surrounded by the six screen plates 112, 113, 114, etc., to provide a series of twelve equally-spaced windows 115, 116, 117, etc., similar to the twelve windows in the screen plate of tube 1. These six screen plates are then connected to a suitable six-phase alternating current source which is synchronized with the six-phase alternating current source at the transmitter. Concentrically surrounding the twelve windows is a unipotential grid 118 which is connected to the transmission channel 93. Concentrically surrounding the cathode, and in alignment with the twelve windows in the screen plates, are twelve output anodes 119, 120, 121, etc., which are connected through respective load resistors 122, 123, 124, etc., and thence through respective coupling condensers 125, 126, 127, etc., to the respective receiving channels 128, 129, 130, etc. The output anodes 119, 120, 121, etc., are connected through their respective load resistors 122, 123, 124, etc., to the positive terminal 131 of the direct current plate power supply 132. The grid 118 can be biased negatively by a suitable direct current supply 133, so that a pulse of plate current does not flow to the respective output anodes except upon the receipt of a positive pulse received from the transmission channel 93, and, if desired, the magnitude of this pulse of plate current can be in proportion to the modulation or amplitude of the received positive pulse.

Fig. 4 shows a modification of the system of Fig. 1, whereby the tube 59 can be eliminated, and the positive pulses for controlling the switching grids 76, 77, 78, etc., can be derived directly from the rotating beam tube. In Fig. 4, the parts or elements which are identical with those of Fig. 1, bear the same designation numerals. In this embodiment, the anodes 23, 24, 25, etc., have their surfaces which face the cathode 3, provided with a coating of material which emits secondary electrons in response to the impingement thereon of the primary electrons from the cathode.

The slat electrodes 17-22 are connected to a suitable six-phase source, and the cathode 3 is biased with respect to the remaining electrodes, to cause the focussed planar beam 49 to rotate at the required rate. Located between the slat electrodes and the anodes, is a cylindrical mesh grid 134 which is connected to a positive terminal 135 of the direct current plate power supply source 136. The anodes 23, 24, 25, are connected through their respective load resistors 44, 45, 46, etc., to another tap 137 on the supply 136. Thus the anodes are at a lower positive potential than the electron collector grid 134. Consequently as the beam 49 rotates, it impinges successively upon the anodes and produces positive pulses at these anodes, and these positive pulses can be coupled through the condensers 53, 54, 55, etc., to control the tube 79 in the manner above described.

While certain particular embodiments have been disclosed herein, various changes and modifications may be made therein without departing from the spirit and scope of the invention.

What is claimed is:

1. A multiplex communication system, comprising, an electron tube having a central electron-emitting cathode, a plurality of separate anodes concentrically surrounding the cathode, means to develop the electrons from the cathode into a beam originating at the cathode and terminating successively at said anodes, means to develop a beam-rotating field to cause said beam to sweep said anodes to develop regularly recurrent pulses at said anodes successively, means to derive from said regularly recurrent pulses another set of switching control pulses synchronized therewith another electron tube having a central electron-emitting cathode and a surrounding anode, a first set of separate grids surrounding the cathode of said other tube, a second set of separate grids in said other tube and surrounding the first set of grids and in radial alignment therewith, a plurality of signal input channels connected respectively to the grids of the first set, a single output channel connected to said anode of said second tube and means to apply said derived pulses respectively and recurrently to said second sets of grids to control successively the conductivity between each grid of the first set and said single anode.

2. A multiplex communication system according to claim 1, in which the electrons from the cathode of the first-mentioned tube are electrostatically focussed to produce a beam which extends radially in one direction only from the cathode to each of said anodes in succession.

3. A multiplex communication system according to claim 1, in which the means to develop the said beam of electrons and the means to rotate said beam, comprises, a plurality of slat electrodes located between the cathode and the anodes with the slat spaces aligned each with a respective anode, and a source of multi-phase potential connected to said slat electrodes to develop a rotating electric field.

4. A multiplex communication system according to claim 1, in which a third electron tube is provided having a central electron-emitting cathode with a plurality of spaced surrounding grids and a plurality of spaced surrounding anodes, means connecting each of the grids of said third tube respectively to the anodes of the first-mentioned tube, and means connecting the anodes of said third tube respectively to the second-mentioned grids of said other tube.

5. A multiplex communication system of the pulse transmission type, comprising, an electron tube of the rotary beam type having a plurality of output anodes for developing regularly recurrent spaced pulses in response to the sweeping of said anodes by said beam, a pulse inverter tube having a plurality of control grids and a corresponding plurality of output anodes for inverting the polarity of said pulses, and a switching and signal control tube having a plurality of signal input grids connected respectively to a series of signal input channels, a corresponding series of switching grids connected respectively to the anodes of said inverter tube, and a signal output channel connected to the anode of said switching and signal control tube.

6. A multiplex communication system according to claim 1, in which the first-mentioned tube has its anodes provided with a coating of secondary electron-emissive material facing the cathode, and means are provided for causing positive pulses to be produced at said anodes in response to the rotation of said beam past each anode.

7. Multiplex communication apparatus, comprising, a first electron tube of the type having a central electron-emitting cathode and a plurality of surrounding spaced anodes, means to focus the beam from said cathode into a substantially flat beam with one edge extending along the cathode and the opposite edge terminating at one of said anodes, means to subject said beam to an electric field to cause it to rotate at a predetermined rate and thereby to generate recurrent pulses successively at said anodes, a second electron tube having a central electron-emitting cathode, a plurality of spaced signal control grids surrounding the cathode, a plurality of switching grids surrounding the control grids and in radial alignment therewith, a single anode surrounding the switching grids, means connecting a plurality of signalling channels respectively to said signal control grids, means to energize said switching grids respectively by said recurrent pulses from the anodes of the first tube, a third electron tube having a central electron-emitting cathode, a plurality of separate anodes concentrically spaced around the cathode of said third tube, a control grid surrounding the cathode of said third tube, means to focus the electrons from the cathode of said third tube into a substantially flat beam having one edge extending along the cathode and the opposite edge extending along the anode of said third tube, means to subject the beam of said third tube to an electric field to cause it to rotate in synchronism with the beam of the first-mentioned tube, a signal transmission channel connecting the anode of said second tube to the control grid of said third tube, and a plurality of signal receiving channels connected respectively to the anodes of said third tube.

8. Multiplex communication apparatus according to claim 7, in which the first-mentioned tube develops said recurrent pulses as negative pulses at its anodes, and a pulse inverter tube is connected between the first and second tubes to convert said negative pulses into positive pulses.

9. Multiplex communication apparatus according to claim 8, in which the inverter tube comprises a central electron-emitting cathode, a plurality of circumferentially-spaced control grids concentrically surrounding the cathode of said inverter tube, a plurality of circumferentially-spaced anodes surrounding the cathode of said

inverter tube and in radial alignment with the grids of said inverter tube, the control grids of said inverter tube being connected respectively to the anodes of the first tube and the anodes of said inverter tube being connected respectively to the switching grids of said second tube.
